CRYSTAL OSCILLATOR CIRCUIT FOR TETRODES

Albert H. Taylor, Washington, D. C.

Application June 15, 1933, Serial No. 675,958

1 Claim. (Cl. 250—36)

(Granted under the act of March 3, 1883, as
amended April 30, 1928; 370 O. G. 757)

This invention relates to crystal controlled vacuum tube oscillators, particularly those designed to function in the type of circuit known to the art as the master oscillator-power amplifier circuit.

5 An object of this invention is to produce a crystal controlled vacuum tube oscillator that is substantially unaffected in frequency by changes in an exteriorly connected load circuit, such as a power amplifier.

10 A further object of this invention is to supply a crystal-controlled vacuum tube circuit utilizing a four electrode-shield grid type of vacuum tube.

15 A still further object of this invention is to provide a crystal controlled vacuum tube oscillator having a greater degree of inherent frequency stability than heretofore obtained in similar circuits utilizing three-electrode vacuum tubes.

20 With the above and other objects in view, the invention consists in the construction, combination and arrangement of parts as will be hereinafter more fully described.

25 Reference is to be had to the accompanying drawing forming a part of this specification which illustrates by a schematic wiring diagram the preferred embodiment of my invention.

30 In the usual design of master oscillator-power amplifier circuits as used in the radio art, it is well known that changes in or adjustments of the amplifier are reflected back into the oscillator, producing frequency changes of greater or less degree depending on the characteristics of the oscillator, the type of tube used, and the general design of the circuit.

35 I have found that such reactions of the amplifier circuit tuning on the frequency of the crystal controlled master may be materially reduced 40 by a special form of coupling to the amplifier circuit when the master crystal controlled tube is a tetrode. The drawing shows a tetrode, which in this case is a 7½ watt shield grid tube, with the crystal connected in the usual way between control grid and ground, the point corresponding to ground being the mid-tap of the transformer secondary 3 supplying voltage to the filament. The screen grid of this tube is not used as a screen but is utilized as a plate or anode whose circuit is tuned by means of a variable inductance 4 and capacity 5 and preferably includes a radio frequency ammeter A. This tunable circuit is grounded through a condenser 12 of .01 microfarad at a point intermediate between the ends of the inductance 4. Adjustable on the in-

ductance 4 there is also connected a balance condenser 6 which is led back to the normal plate of the oscillator tube.

5 This crystal circuit, when supplied with voltage on the screen only, oscillates in the usual manner when the output circuit, 4 and 5, connected to the screen, is properly tuned to the crystal frequency. At the same time, the balance condenser 6 can be adjusted in pick-off and capacity so as to supply a reversed electric coupling to the plate, exactly neutralizing the electric coupling between screen and plate. Thus there is neither magnetic nor electrical coupling between the tuned screen circuit and the plate.

10 The plate is connected through a stopping 15 condenser 7 to the grid 15 of the amplifier tube which may be operated either as a straight amplifier or as a frequency doubler, as desired.

15 When there is no voltage present on the oscillator tube plate as when the switch 13 is open, and no magnetic nor electrical coupling between that plate and the crystal oscillator circuit, the grid 15 of the amplifier tube will receive no excitation. By means of a potentiometer 8 placed 20 across the high voltage supply for the crystal oscillator tube, various potentials may be supplied to the screen and plate of that tube. These potentials can be then adjusted until a certain percentage of the electron stream will flow through the screen grid and strike the plate, thus giving 25 an adjustable coupling to the grid of the amplifier tube. This coupling is what may be called an electron stream coupling to distinguish it from a coupling by means of a variable magnetic or electric field of the usual type. This adjustable coupling, by means of the electron stream which 30 flows through the meshes of the screen, enables one to get a crystal controlled oscillating circuit which is substantially independent of the changes 35 in load or tuning of the amplifier system.

40 It will be noted that the working grid of the amplifier tube is provided with a choke 11 and is also negatively biased. A sensitive direct current instrument 14 in series with the negative lead to this amplifier grid indicates whether or not that 45 grid has excitation. If, then, when the plate supply of the first tube is disconnected, leaving only the screen with high voltage, the balance condenser 6 is adjusted until the direct current meter 14 reads zero, the circuit is balanced, that is, the 50 electric coupling within the crystal controlled oscillator tube between screen and plate has been neutralized and any subsequent coupling must be by means of the electron stream which flows 55 through the meshes of the screen. The amount of

this electron stream coupling can naturally be regulated by the voltage on the plate of the oscillator tube which can be at a slightly higher voltage than the screen but more often is considerably lower than said screen.

Ordinarily, for simplifying operation, the voltage to the plate of the oscillator tube is fed through a radio frequency choke 9 but the output of the circuit, that is to say, its ability to deliver excitation to the amplifier grid 15, may be greatly enhanced, as shown in the diagram, by substituting for the radio frequency choke 9 a parallel tuned circuit 10. It has been found, however, that in this case the freedom from reaction is not quite as good as if the choke 9 were used.

It is very important that the different parts of this circuit be kept screened from each other, as shown by screen 16. In particular, the main oscillator circuit must be screened from the parallel tuned inductance 10 in the plate of that same tube, if such be used in place of the choke 9. Both of these circuits must be screened from the output of the amplifier tube if that tube is amplifying at the same frequency. This is not important, however, if the second tube is used as a frequency multiplier.

It is obvious from the foregoing that with this particular tetrode balanced circuit and by means of its electron stream coupling, a greater stability of the crystal oscillator circuit is obtained, together with an improved degree of freedom from tuning and load reactance in the amplifier circuit. This permits a strong coupling to be used between master oscillator and amplifier without the consequent reaction having an influence on the frequency. While it is realized that no crystal controlled circuit is seriously influenced in frequency by tuning or load reaction in a system amplifier, nevertheless, for work of high precision the matter is at times troublesome.

We are dealing here with an effort to improve small variations in frequency of the order of 0.01%.

It will be noted that in this particular circuit one side of the crystal holder can be kept at ground potential, simplifying the design when a multiplicity of crystals are to be used in the transmitter. In such cases it is highly desirable to keep the base plate of the crystals at ground potential in order that all crystals may be mounted on a common metal plate acting as a heat equalizer within the temperature control box.

It will be understood that the above description and accompanying drawing comprehend only the general and preferred embodiment of my invention, and that various changes in construction, proportion and arrangement of parts may be made within the scope of the appended claim, and without sacrificing any of the advantages of my invention.

The herein described invention may be manufactured and used by or for the Government of the United States for governmental purposes without the payment to me of any royalties thereon.

I claim:

In an oscillation generator, a four-electrode vacuum tube having a cathode, a control grid, a grid-like anode, and a plate, a frequency determining control grid circuit, an oscillatory circuit, a direct current conductive path between a first point on said oscillatory circuit and said grid-like anode, a variable capacitative connection between a second point on said oscillatory circuit and said plate, and a fixed capacitative connection between a third point on said oscillatory circuit and ground, said third point being intermediate said first and second points.

ALBERT H. TAYLOR. 40
